UNITED STATES PATENT OFFICE

HERBERT G. IRWIN, OF AMARILLO, TEXAS

CARBIDE AGITATOR FOR ACETYLENE GENERATORS

Application filed August 6, 1927. Serial No. 211,034.

This invention relates to improvements in acetylene generators of the carbide to water type in which an automatically controlled valve regulates the gravitation of granular carbide from a carbide container into a water container, the rate of carbide feed being determined by the rate of consumption of acetylene generated. The automatic feed control being the opposed gas pressure type where-
 5 in a flexible diaphragm is arranged between two independent gas pressures whereby variation in one of the pressures will cause a movement of the diaphragm. The latter being connected so that its movement will
 10 effect the operation of a carbide feed valve.

While the opposed gas pressure type of automatic feed control is believed to have a safety advantage over the spring pressed diaphragm control, it has a drawback simi-
 15 lar to the latter in that the feeding of carbide is more or less intermittent. The carbide grains being rough and crowded together in the small end of the conical bottom of the carbide hopper where the feed valve is located
 20 often hang among themselves, thus failing to respond immediately to the regulating movements of the feed valve. The variation in pressure in the generator required to move the feed valve any great extent to start the flow of carbide and to shut off the flow is ob-
 25 jectionable in that a constant pressure or a near constant pressure in the generator is most desirable.

The object of my invention is to provide
 30 new and useful improvements in the automatic opposed gas pressure valve feed type of acetylene generator.

A further object of my invention is to over-
 35 come the usual two to five pounds variation in working pressure in the automatic valve feed type of acetylene generator.

A further object of my invention is to over-
 40 come the intermittent feeding of carbide in the automatically controlled valve type of carbide feeds.

A further object of my invention is to prevent a mass of carbide grains lodging in the vicinity of the feed valve and hindering the feeding of carbide.

50 A further object of my invention is to pro-

vide an auxiliary to the valve type of carbide feeds by which granular carbide will feed in a thin stream.

With these and other objects in view, my in-
 55 vention consists in the arrangement, combina-
 tion and construction of the various parts of
 my improved device, as described in the speci-
 fication, claimed in the claims, and shown in
 the accompanying drawings, in which:

Figure 1 is a sectional view of the upper
 60 portion of an acetylene generator showing a
 carbide agitator constructed in accordance
 with my invention.

Figure 2 is an enlarged sectional view of
 65 certain parts of the carbide feed and con-
 trol such as shown in Fig. 1.

Figure 3 is a sectional view through the up-
 70 per portion of an acetylene generator show-
 ing an alternate form in which my invention
 may be accomplished.

Figure 4 is a sectional view of a type of
 75 check-valve that may be used as a gas flow
 interrupter.

Figure 5 is a sectional view through the up-
 80 per portion of an acetylene generator show-
 ing another form in which my invention can
 be worked out.

 phragm spring used in the mechanisms
 shown in Figs. 1, 3, 5, 6, 7, 9, 10 and 11.

Figure 13 shows a removable plate used in the vibrators shown in Figs. 6, 7 and 10.

Referring to the accompanying drawings, I have used the letter "A" to indicate generally the carbide feed control diaphragm and the letter "B" to indicate the vibrator diaphragm. Numeral 1 indicates the carbide hopper and 2, the water chamber of an acetylene generator.

In Fig. 1 the automatic feed control is mounted inside the carbide hopper immediately above the carbide feed outlet and it consists of a pressure tank 3, the diaphragm "A", a piston 4, a valve stem 5 and feed valve 6, a removable housing 7 and a communicating pipe 8. The piston and diaphragm form the pressure responsive element of the feed control. The control diaphragm in this instance is a hollow open ended cylinder in form, being cut the desired length from soft rubber tube stock having qualities of toughness and durability. It has one end secured gas tight about the upper end of the piston by a suitable band clamp 4C, best seen in Fig. 2. Six to eight rounds of small round wire wound on tightly with opposite ends of the wire soldered to the adjacent outside wire at opposite sides of the winding will serve as a band clamp for the diaphragm. The opposite end of the control diaphragm is stretched outwardly and over the lower beaded edge of the cup portion 3D, of the pressure tank and secured gas tight to the outer periphery of the cup by a band clamp similar to 4C. The valve stem 5 is made integral with the piston and it depends from the under side of the piston head. The carbide feed valve 6 screws onto the lower end of the valve stem and is made secure by fusing solder in the screw-threads. The upper end of the housing 7 is secured to the pressure tank by suitable ears and bolts not shown. This housing extends down over the feed control to about one inch of the hopper bottom 10. One end of the spiral piston spring 11, presses against the under side of the piston head and its other end seats upon the upper side of the web 12, which latter is removably mounted in the lower end of the control housing. One end of the pipe 8 screws in to the side of the pressure tank immediately above the upper end of the cup 3D and it extends outwardly through a packing gland 13, in the wall of the carbide hopper. An angle needle valve 14, is screwed onto the outer end of the pipe 8. The small angle pipe 15, connects the needle valve with the interior of the carbide hopper. Through the pipe 8, needle valve 14 and pipe 15 the pressure tank 3 may communicate with the interior of the carbide hopper. The pipe 9 is formed integral with the pressure tank and extends inward of the pressure tank to the center of the head of the cup 3D at which place it is angled to extend through the head of the

cup and is fused to the inner surface thereof. The outer portion of the pipe 9 extends through the packing gland 13C, in the wall of the carbide hopper and terminates in an outside threaded end onto which a diaphragm vibrator is screwed. The pipes 8 and 9 extend in line and the packing gland 13C in the side of the carbide hopper is diametrically opposite to the gland 13. The pressure tank is removable from the carbide hopper by removing the pipe 8 and moving the tank laterally toward the gland 13 to withdraw the pipe 9 from the gland 13C. Removable braces not shown attach to the upper end of the pressure tank holding the same against movement when in place. The vibrator consists mainly of a housing composed of two separable sections 16 and 16H, a diaphragm "B" and a saucer shaped spring "J". The vibrator diaphragm is a flat disc preferably cut from soft sheet rubber stock having qualities of toughness and durability or molded in flat disc form of suitable rubber gum stock. The back section 16 of the vibrator housing is a cupped disc in form, its edge terminating in a flat circumferential flange provided with spaced holes to receive clamping bolts. The front section 16H is a flat disc provided with bolt holes in a margin adjacent its outer edge that register with the bolt holes in the flange of the section 16. The outer marginal edge of the diaphragm extend between the housing flanges and bolts extending through the flange holes and diaphragm clamp the two sections of the vibrator housing upon the diaphragm and together, the diaphragm forming a flexible partition between the housing sections. The vibrator spring "J" may be cut from thin sheet stock of nonrusting spring metal, with equally spaced radial slits in its outer portion to form narrow spring sectors. The sectors are all curved in one direction to give the spring a saucer like shape. This spring is placed between the housing section 16H and the diaphragm with the incurved side toward the housing member and the out-curved side of the spring toward the diaphragm. The vibrator spring presses the center portion of the diaphragm into the hollow of the housing section 16 giving the diaphragm a concavo-convex shape. The angle pipe 17, connects the vibrator with the gas outlet pipe 18, of the generator. The convex side of the vibrator diaphragm "B" communicates with the control diaphragm "A" and piston 4 through pipe 9 and the concave side of vibrator diaphragm communicates with the gas outlet pipe 18 through pipe 17. The pressure tank communicates with the feed control piston 4 and a diaphragm through a small aperture 19, in the wall of the pipe 9 adjacent the inner angled end thereof as will be seen upon reference to Fig. 2. A hand feed comprising a thin

round rod poker 28, extending into the carbide hopper through a packing gland and tubular guide not shown here, but shown in Figs. 5 and 9, is provided to open the carbide feed valve to feed carbide from the hopper into the water chamber to raise the initial operating pressure. In getting the operating pressure the needle valve 14 is opened so gas as it is generated may flow 5 into the pressure tank and be of the same pressure as gas in the generator. Up to fifteen pounds pressure per square inch in an acetylene generator is usually sufficient for ordinary use. And when the desired 10 pressure is reached through the use of the hand feed the needle valve 14 may be closed and the operation of the hand feed discontinued. The closing of the needle valve confines the gas in the pressure tank which gas is 15 used to oppose gas in the generator to give motion to the control diaphragm. Thus it will be seen that by drawing gas from the generator the pressure in the generator will be lessened and pressure due to gas confined 20 in the pressure tank will push the piston 4 downwardly against the pressure of the spring 11 which will open the carbide feed valve a distance sufficient to feed carbide. And presently, as common with the valve 25 type of carbide feeds, the flow of carbide exceeds the proper amount to generate acetylene in true proportion to the rate at which acetylene is being drawn off. The pressure in the generator begins to rise rapidly, pushing 30 the piston upwardly which closes the feed valve and thus cutting off the flow of carbide. As consumption of gas continues the pressure in the generator goes down until the feed valve is again opened a distance 35 sufficient to feed more carbide and presently the same objectionable rise in pressure occurs. Such is common with the ordinary valve type of carbide feeds. It seems that grains of pea size carbide will flow hardly 40 or not at all until the feed valve is opened a certain distance and then the flow is too much for the usual rate of consumption.

If grains of pea size carbide had qualities 45 of moving with such freedom among themselves as do some other thin substances, the grains would gravitate in a well regulated stream past a feed valve and the intermittent feeding would not occur with the usual valve feed. The pressure in the generator would 50 remain near constant after the feeding position of the feed valve was reached. But grains of pea size carbide as it is found on the market do not move with sufficient freedom among themselves to feed in a thin stream past the usual feed valve in an acetylene generator without being kept in motion or moved at close intervals in the vicinity of 55 the feed valve.

The invention here is a vibrant gas pressure 60 on the side of the carbide feed control

diaphragm communicating with the pressure tank. This gives the control diaphragm in addition to its usual feed controlling movements a revibrating short motion which is transmitted to the carbide in the vicinity of the feed outlet through the medium of the valve stem and feed valve. Of course something movable other than the feed valve may be placed in contact with carbide in the vicinity of the feed outlet and used to get motion to carbide directly from the vibrator, but the feed valve is already there and might as well be used for that purpose also when connection between the vibrator diaphragm and feed control diaphragm can be made 70 without wear as in the present device.

In Fig. 1, gas from the pressure tank presses on the convex side of the vibrator diaphragm the same as on the feed control piston and diaphragm. When pressure in 75 the generator is less than pressure in the pressure tank the vibrator diaphragm yields also, but not so much as the feed control piston and diaphragm yields. The spring "J" being stronger than the spring 11, the vibrator diaphragm moves only half its limit when the control piston has reached its downward limit. The gas outlet pipe 18 of the generator has a large ball check valve 20, immediately outside the wall of the generator. This 80 valve is used in the capacity of an automatic gas flow interrupter. When gas is drawn from the generator through the outlet pipe 18 this interrupter valve 20 generates small pressure waves in the gas flow, which waves are used to operate the vibrator. These 85 pressure waves reach the concave side of the vibrator diaphragm through the pipe 17. Such means for operating a diaphragm 90 vibrator is described in my pending application Serial No. 4,935. The operation of the vibrator diaphragm as result of pressure waves in the gas outlet set up similar pressure waves on the pressure tank side of the feed control piston and diaphragm through gas 95 under pressure in pipe 9. Thus it will be seen that the feed control piston will vibrate in 100 harmony with the vibrator diaphragm, giving the feed valve short up and down movements which agitate carbide in the vicinity 105 thereof. It will be understood that the pressure waves in the gas outlet are constant while gas is being drawn from the generator and consequently the operation of the vibrator, the feed control and the agitating motion 110 of the feed valve is constant while gas is being drawn from the generator. The carbide feed regulating movement of the feed valve occurs only when there is variation in 115 pressure in the generator. In other words the feed control including the feed valve perform their feed regulating movements in a state of vibration. The function of the feed 120 control and feed valve is now dual, in the operation of agitating carbide and regulating 125

130

the carbide flow. Granular carbide flows so regular in agitation that at a constant rate of consumption of gas the feed valve has but slight variation in position from its seat, unless consumption of gas is either increased, decreased or discontinued. When consumption of gas is increased the pressure in the generator is lowered slightly, to which the feed control immediately responds by lowering the feed valve accordingly increasing the rate of carbide feed. When consumption of gas is discontinued the pressure of gas in the generator rises slightly, due to the generation of gas from the last of the carbide grains to fall into the water chamber. The rise in pressure causes the feed control to move the feed valve upwardly toward its seat. But not necessarily close the feed valve for the interrupter ceases operation and there is no agitation of carbide when consumption of gas is discontinued. Without agitation the feed valve may stand open a certain distance without feeding carbide. Also, though the operation of the interrupter accelerates with increase in consumption and likewise the agitation of carbide is increased, good results may be had by agitating carbide at a constant rate irrespective of the rate of consumption of gas.

In Fig. 3, the automatic feed control is mounted outward of the carbide hopper and it consists for the most part of a pressure tank 3, the control diaphragm "A", a valve stem 5, a carbide feed valve 6 and a removable housing 7E. The feed control diaphragm in this instance is a flat disc preferably cut from soft sheet rubber stock having qualities of toughness and durability or molded and cured in flat disc form of suitable rubber gum stock. The outer margin of the control diaphragm is clamped between the lower outwardly extending flange of the housing 7E and the top of the carbide hopper. The saucer shaped radial leaf spring 11K between the control diaphragm and hopper head has its outcurved side pressing on the under side of the control diaphragm giving the latter a concavo-convex shape. The upper end of the valve stem 5 provided with screwthreads and fitted with nuts clamp onto the center of the control diaphragm, also clamping the diaphragm and spring together. The partition 7C, in the housing 7E limits upward movement of the control diaphragm and the top of the carbide hopper limits downward movement of the control diaphragm. At the center of the partition is a large opening which permits free play of gas from one side to the other of the housing. The pressure tank communicates with the interior of the housing 7E through the pipe 22 and small aperture 19. The pressure tank may communicate with the interior of the carbide hopper through the short length of pipe and needle valve 14.

The vibrator diaphragm "B" is mounted immediately above the partition 7C in the upper end of the housing 7E. The marginal edge of the vibrator diaphragm being clamped between the outwardly extending flange at the upper end of the diaphragm housing and the flat disc closure 16H. The vibrator spring "J" is disposed between the vibrator diaphragm and closure with the outcurved side of the spring toward the diaphragm. Thus the convex side of the vibrator diaphragm is toward the control diaphragm and exposed to pressure from the pressure tank. The concave side of the vibrator diaphragm communicates with the gas outlet pipe 18 through the pipe 17.

A hand feed similar to that shown in Figs. 5 and 9 may be provided to open the carbide feed valve 6 in Fig. 1 to feed carbide into the water chamber in raising the initial working pressure. The needle valve 14 being left open so gas may fill the pressure tank and space 23 between the control and vibrator diaphragms. When the desired pressure is reached through the use of the hand feed it may be discontinued and the needle valve 14 closed. The closing of the needle valve confines gas in the pressure tank and space 23. Then by drawing gas from the generator through the outlet pipe as in use, gas pressure in the generator and pressure on the under side of the control diaphragm will be lessened. Gas pressure in the pressure tank and space 23 will push the control diaphragm downwardly depressing the spring 11K and through the medium of the valve stem 5 will open the carbide feed valve 6 which will admit carbide into the water chamber, thus generating more acetylene. Gas in space 23 and from the pressure tank presses on the convex side of the vibrator diaphragm the same as on the control diaphragm. But the vibrator diaphragm spring should be stronger than the control diaphragm spring so the vibrator diaphragm will not reach its depressed limit before the control diaphragm reaches its depressed limit. Thus the vibrator diaphragm will have room to vibrate up to and beyond the depressed limit of the control diaphragm. In drawing gas from the generator through the gas outlet pipe the flow interrupter 20, same as in Figs. 1 and 4, generates small pressure waves in the gas flow, which waves reach the concave side of the vibrator diaphragm through the pipe 17, putting the vibrator diaphragm in vibration. Thus gas in space 23 is made to vibrate in pressure, causing the control diaphragm to vibrate in a manner much the same as the vibrator diaphragm. Through the valve stem and feed valve the vibrant energy given the control diaphragm reaches carbide in the vicinity of the feed outlet causing carbide grains to feed uniformly at a reduced rate. The feed valve opens a certain distance, de-

pending on the rate gas is drawn off, and stands in vibration. The carbide grains gravitating gradually in a thin stream past the feed valve.

The pressure tank 3, in Fig. 3 may be eliminated if desired and the housing 7E extended upward from the partition 7C so as to provide a space for gas of about such volume as the pressure tank would hold. While a large volume of gas to press on the convex side of the control diaphragm is not necessary, the volume of gas should be such that the displacement of the diaphragm will not lower the depressing pressure more than one pound per square inch. The needle valve 14 may be connected as shown in Fig. 5. Without the pressure tank and with the extended housing 7E the operation of the vibrator and control would be very near the same. The loss of vibrant energy in the large volume of gas between the two diaphragms being small.

In Fig. 5 the feed control diaphragm is mounted upon the carbide hopper, the spring 11K being the same as that in Fig. 3 and mounted in a similar manner. From the partition 7D upward of the control housing comprises a pressure tank 3. The partition 7D instead of having a large opening as in partition 7C, Fig. 3, is closed against communication between the pressure tank and control save a small aperture 19 in the wall of pipe 9 at the inner angle end thereof. The pressure tank may communicate with the interior of the carbide hopper through the needle valve 14. The vibrator in this instance is mounted on the upper end of an upright tank 25. The outer marginal edge of the vibrator diaphragm "B" being clamped between outwardly extending flanges of the vibrator tank 25 and the cup shaped housing 16 of the vibrator as will be seen in Fig. 6. The concave side of the vibrator diaphragm and spring "J" is toward the vibrator tank. The outer edge of the spring leaves work upon the face of the removable flat disc 16X, which is supported in the upper end of the vibrator tank by a narrow annular shoulder 26. The upper extremity of the rod 27 is provided with a wide flat head and it clamps onto the center of the vibrator diaphragm by means of a nut and screw threads. This rod 27 extends downward into the vibrator tank near the bottom thereof. To the lower end of this rod clamped by washers, nuts and screw threads is a thick flat disc 28 which will be called a trembler. The diameter of the trembler should be slightly smaller than the inner diameter of the tank so as to permit some side motion and it may consist of wood, cork or other suitable light material treated with a drying oil under pressure to make it impervious to water. The vibrator tank is connected in the gas outlet 18 first in line from the generator. It is filled with a liquid such as water to a level with the fill plug 25C. And owing

to the position of the tank on the generator and to prevent the liquid running out of the tank into the generator the outlet pipe is angled upward immediately outside the generator to a point some distance above the liquid level of the tank and the pipe returns to the bottom of the tank as indicated by the dotted lines 18. The outlet 18E from the vibrator tank may lead to the usual flash-back tank not shown. The convex side of the vibrator diaphragm communicates with the pressure tank side of the control diaphragm through the pipe 9. Extending at an angle through the wall of the carbide hopper toward the carbide feed valve 6 in a tube provided with a suitable packing gland is a small round rod poker 29. The lower end of the poker abuts the feed valve pushing the latter open when pressed in by the hand-hold 29C. Thus carbide in the hopper may be fed by hand into the water chamber to generate acetylene for the initial working pressure in the generator. The poker engages the feed valve at an angle pushing the latter downwardly to the side and not open enough to permit a continual flow of carbide into the water chamber. As a safety feature, it is thus necessary to work the poker back and forth a number of times to get enough carbide into the water chamber to raise the desired pressure. When the working pressure is reached the poker may be pulled outwardly a short distance so the lower end will be out of the way of carbide about the feed valve. In operating the hand feed, the needle valve 14 should always be in open position so gas from the generator may fill the pressure tank. However, the needle valve 14 should be closed after the working pressure is reached so as to confine gas in the pressure tank at the proper pressure. Now upon drawing gas from the generator the pressure in the generator will be lessened. Consequently the pressure on the under side of the control diaphragm will be lessened and gas confined in the pressure tank will push the control diaphragm downwardly opening the feed valve to feed more carbide into the water chamber. In drawing gas from the generator through the gas outlet, gas flows into the vibrator tank at the bottom and upward around the trembler through the liquid in the tank and out at 18E. Gas bubbling upward around the trembler through the liquid in the tank gives a jerky motion to the trembler and through its connection with the vibrator diaphragm causes the diaphragm to vibrate. The operation of the vibrator fluctuates gas pressure on the pressure tank side of the control diaphragm through the pipe 9, causing the control diaphragm to vibrate in a manner similar to the vibrator diaphragm. Through the valve stem and feed valve the vibrant energy of the control diaphragm reaches carbide in the vicinity of the feed valve.

The vibrator and vibrator tank shown in Fig. 7 is substantially the same as that shown in Fig. 6 except a float 30, is mounted movably on the vibrator rod 27 to operate on top of the liquid in the tank instead of a trembler which operates submerged as in Fig. 6. The float 30 may be made of thin sheet metal as will be seen in Fig. 8, or it may be made of cork or other suitable buoyant material. Three grooved rollers "T", "Y" and "Z", carried by brackets on the float movably engage the rod 27. The roller "Z" mounted on a pivoted bracket having a tension spring "N" engages the opposite side of the rod from the rollers "T" and "Y". The tension spring pulling upon the roller brackets press the rollers against the rod whereby the float may move with certain resistance up and down on the rod so as to keep with the liquid level in the tank in case the level is lowered through evaporation or otherwise and yet have sufficient grip on the vibrator rod to work the vibrator diaphragm when the liquid in the tank is in a state of agitation. It will be seen that gas flowing upward through the liquid in the tank will cause the float to work in short up and down movements and through its connection with the vibrator diaphragm will work the diaphragm in much the same manner.

The feed control diaphragm in Fig. 9 is substantially the same as that in Figs. 3 and 5 and mounted in much the same manner. The pressure tank 3 in this instance is built onto the vibrator housing 16 and it communicates with the control diaphragm through the aperture 19 and pipe 9. The vibrator diaphragm communicates with the control diaphragm through the pipe 9 also. The vibrator tank 25 is mounted in the gas outlet first in line from the generator. In this instance the gas inlet 18 and outlet 18E of the vibrator tank is the reverse in position on the tank to that in Figs. 5, 6 and 7. Connected with the vibrator diaphragm and spring "J" on the concave side and at the center thereof is a cage 31, having therein a ball 32, upon a seat 33, in the base of the cage, as will be seen in Fig. 10. A gas bell 34, depends from the base of the cage and its sides extend down into the vibrator tank to a short distance of the bottom of the tank. The gas outlet 18E of the vibrator tank extends through the bottom of the tank and upward into the open end of the gas bell to a point near and directly under the ball valve 32. A round rod 35 passing through a packing gland 36 in the outside angled portion of the pipe 18E extends upward through the center of the inner portion of the pipe and screws through the closed upper end of the pipe. The screw threads on the upper end of the rod permit endwise adjustment of the rod whereby the upper end may be moved toward and away from the ball valve 32. Openings 37, in the

wall of the inner portion of the pipe 18E immediately under the closed end thereof admit gas from the bell into the pipe. The vibrator tank may be filled with water or other suitable liquid to a level with the fill plug 25C. The outer angled end of the gas outlet of the tank may be connected with the usual flash-back tank not shown. It might be well to explain that on the usual flash-back tank will be found the gas cut-off valve and other service connections through which gas from the generator may be drawn for use. The pressure tank 3 may be filled with gas from the carbide hopper through the needle valve 14, pipe 9 and aperture 19. The initial working pressure in the generator shown in Fig. 9 may be raised with the hand feed the same as in Fig. 5. Before raising the working pressure the adjusting rod 35 of the vibrator tank should be screwed up so as to hold the ball 32 slightly off its seat. This passes gas by the valve into the bell 34 and throughout the outlet without working the bell and vibrator diaphragm. The vibrator may be adjusted for operation while drawing gas from the generator by screwing the rod 35 downwardly until repeated taps on the rod occurs. Screwing the rod 35 downwardly moves the upper end of the rod away from the ball allowing the valve to close. The valve being closed and the lower open end of the bell sealed in the liquid in the tank, gas presses on the upper end of bell moving the bell downwardly bringing the ball in contact with the upper end of the adjusting rod which opens the valve again, allowing gas to flow into the bell equalizing pressure on both sides thereof. Through connection with the vibrator spring and diaphragm the downward movement of the bell depresses the diaphragm and spring and upon unseating the ball the vibrator spring lifts the bell permitting the ball to seat again, whereupon gas on the outer side of the bell immediately presses the bell down and again unseating the ball. These movements are repeated continually in rapid succession giving motion to the vibrator diaphragm while gas is being drawn from the generator. Through gas in the pipe 9 the control diaphragm is induced to operate in a manner similar to the vibrator diaphragm. The control diaphragm may function to open and close the carbide feed valve in a state of vibration. But, in vibration the usual intermittent movements of the control diaphragm and feed valve which feed carbide intermittently are absent, due to the regularity in which carbide grains gravitate in a state of agitation.

The gas bell 34 in Fig. 10 will function to operate the vibrator diaphragm without the valve 32 and 33 and rod 35, by using a heavier vibrator spring and lowering the liquid level in the vibrator tank to a point not so high above the open end of the bell. The upper

end of the bell being without the valve and closed, gas will flow under the lower edge of the bell and upward through the liquid in the lower end of the bell to reach the upper end of the outlet 18E. Gas in passing upward through the liquid in the lower end of the bell gives the bell a jerky movement which operates the vibrator diaphragm.

The vibrator may be mounted submerged in the liquid in the usual flash-back tank as shown in Fig. 11. In this instance the vibrator is similar to that shown in Fig. 1 in structure. Its position in the tank is near the bottom thereof facing the gas inlet to the tank. The concave side of the diaphragm being exposed to gas and liquid in the tank through a large opening in the section 16H of the vibrator housing. The convex side of the vibrator diaphragm may communicate with the feed control diaphragm through the pipe 9. Gas flowing upward around the vibrator through the liquid in the tank gives motion to the vibrator diaphragm by agitating the liquid in the tank.

While I have shown and described several devices constructed in accordance with my invention, it will be manifest to persons skilled in the art that many changes may be made in minor details of structure in adapting the device to various use, and slight changes in the mode of operation of same within the scope of the appended claims, without departing from the spirit of the invention; it is, therefore, to be understood that this invention is not to be limited to the details described and shown.

What I claim is:—

1. In a carbide agitator for an acetylene generator, the pressure responsive element of a carbide feed control comprising substantially a pressure responsive diaphragm and a pressure tank with communication between said tank and diaphragm restricted to a narrow passageway, and means for rapidly fluctuating the pressure on the pressure tank side of said diaphragm in addition to the usual pressure change in the generator to which said diaphragm is responsive to control the rate of carbide feed.

2. In a carbide agitator for an acetylene generator, a pressure responsive carbide feed control diaphragm having one side thereof exposed to gas pressure in the generator and connected with a carbide feed valve and the opposite side of the diaphragm exposed to gas pressure of a pressure tank, a second diaphragm having one side thereof communicating with the pressure tank and the pressure tank side of the first named diaphragm, and means for conducting pressure fluctuations of a flow of gas to the opposite side of the second diaphragm for vibrating same.

3. In a carbide agitator for an acetylene generator, a pressure responsive carbide feed control diaphragm disposed between gas pres-

sure of said generator and gas pressure of a pressure tank, a diaphragm vibrator, and tubular means of communication between the pressure tank side of said control diaphragm and one side of the diaphragm of said vibrator.

4. In a carbide agitator for an acetylene generator, a pressure responsive carbide feed control diaphragm connected on one side with a carbide feed valve and disposed between two independent gas pressures, a diaphragm vibrator, a gas pressure connection between one side of the diaphragm of said vibrator and the side of said control diaphragm opposite to the side connected with said feed valve.

5. In a combined carbide agitator and automatic carbide feed control for an acetylene generator, a gas pressure tank with means for introducing gas into said tank and means for confining gas in said tank, a carbide feed control diaphragm having one side thereof exposed to gas pressure from the gas generating chamber of the generator and connected with a carbide feed valve and the opposite side exposed to the pressure of gas confined in said pressure tank, a second diaphragm having one side thereof exposed to the pressure of gas confined in said pressure tank, and means for vibrating said second diaphragm while gas is being drawn from the generator when the gas pressure in the generator is below the pressure of gas confined in said pressure tank.

6. In combination, an acetylene generator having an automatic carbide feed control including an elastic fluid pressure tank and means responsive to change of gas pressure in the generator, a container adapted to receive a liquid, a vibrator comprising a float disposed in said container and connected with a diaphragm having one side thereof exposed to the pressure of fluid in said pressure tank, and means for conducting a flow of gas from said generator through liquid in said container to vibrate said float.

7. In combination, an acetylene generator having an automatic carbide feed control including an elastic fluid pressure tank and means responsive to change of gas pressure in the generator, means for conducting a flow of gas under pressure from the generator, means for fluctuating the pressure of the gas flow, and means responsive to change of pressure in the gas flow for fluctuating the pressure of the fluid on the pressure tank side of the first named pressure responsive means.
